ENGRAVING TOOL

Miguel de la Torre, New Haven, Conn., assignor,
by mesne assignments, to Burgess Battery Company, Chicago, Ill., a corporation of Delaware

Application March 22, 1940, Serial No. 325,445

7 Claims. (Cl. 78—13.1)

My invention relates to new and useful improvements in engraving tools.

An important object of my invention is to provide a tool for engraving, burning, beating, or embossing glass, metals and like materials, which may be electrically operated from any convenient source of current supply.

Another object of my invention is to provide a tool of the above-mentioned character which includes an engraving point and means to impart a vibratory motion to the point, which means is simple and compact in its construction to promote efficient operation and inexpensive manufacture of the device.

Still another object of my invention is to provide a tool of the above-mentioned character which may be safely and satisfactorily operated by expert or inexperienced persons, the association of parts being such that it will not be necessary to press the engraving point into the work but only necessary to slide the point along the surface to be engraved, the inherent weight of the tool coupled with the vibratory motion of the point being sufficient to perform the engraving operation.

Other objects and advantages of my invention, will be apparent during the course of the following description.

In the drawing, forming a part of this specification, and wherein like numerals are employed to designate like parts throughout the same,

Figure 1 is a side elevation of a device embodying my invention,

Figure 2 is a longitudinal sectional view taken on the line 2—2 of Figure 1,

Figure 3 is a bottom plan view of my device,

Figure 4 is a fragmentary side elevation, showing parts in section, and illustrating a modification of the clamping means for holding the engraving needle,

Figure 5 is a transverse sectional view taken on the line 5—5 of Figure 4, and

Figure 6 is a fragmentary side elevation of my device, and showing an attachment incorporated therewith for burning the surface of the work.

In the accompanying drawing, wherein for the purpose of illustration, is shown a preferred embodiment of my invention, the numeral 10 designates a motor casing which is of substantially rectangular formation in elevation to accommodate the laminated metallic core 11. The core is of conventional shape and construction being formed with longitudinally spaced slots 12 and 13 which define a middle leg portion 14 around which the coil of wire 15 is wound and from

which the coil is insulated by the material 16. The side walls of the casing are bowed outwardly, as at 17 and 18, to accommodate the laterally extending portions of the core and the ends 19 of the core extend outwardly of the casing and are adapted to be connected with any suitable source of current supply. The top wall 20 of the casing is spaced substantially above the core and windings to define the armature chamber 21, which chamber is of substantially greater depth than the armature 22 arranged therein. The end 23 of the armature is held in close proximity to the core by the inwardly extending clip 24 which engages the same in a manner to hold the said end of the armature in an essentially pivotal relation with the casing and to permit the opposite end 25 of the armature to have a substantially free oscillatory movement between the top of the core and the top wall 20 of the casing. An adjusting screw 26 is carried by the top wall 20 adjacent the end 25 of the armature and the inwardly extending end thereof is adapted to be contacted by the armature. The extending end of the screw may be advanced or retracted to limit the oscillatory movements of the vibratory end of the armature.

The depending tube 27 is welded, or otherwise secured, to the bottom wall of the casing below the end 25 of the armature. A sleeve 28, of a suitable insulating material, is snugly pressed over the tube 27 and with its upper end 29 abutting the bottom wall of the casing. The lower end 30 of the insulating sleeve extends substantially beyond the tube 27 and the extending portion is enlarged and formed with an internally screw-threaded bore 31, which bore is of slightly larger diameter than is the tube 27. A bushing 32 is threadedly received within the bore 31 and the lock nut 33 is carried by the bushing and adapted to be moved into abutting engagement with the lower end 31 of the insulating sleeve to fix the movement of the bushing in a selected, advanced or retracted position.

A driving rod 34 extends through the bushing, through the tube 27 and into the armature chamber 21 below the oscillating end 25 of the armature, and a coil spring 35 is interposed between the inner end of the bushing 32 and the annular collar 36 formed on the rod and peripherally engaging the inner bore of the tube 27. The resilient action of the spring urges the end 38 of the driving rod into pressed engagement with the bottom face of the armature and acts to hold the vibrating end of the armature against the inwardly extending end of the adjusting screw 26.

The portion of the driving rod extending through the bushing is enlarged to constitute a head portion 37 adapted to snugly, but slidably, engage the inner bore of the bushing. The portion of the head extending beyond the bushing is provided with an end recess 38 to receive the engraving needle 39 and a set screw 40, carried by and extending laterally from the head is adapted to secure the needle within the recess.

When an alternating current is supplied to the winding 15, a magnetic field will be created to alternately attract and repel the armature 22. The effect on the armature will be to produce a vibratory actuation of the end 25 thereof and the vibration of the armature in the above manner will produce an axial vibration of the driving rod 34 which operates against the resilient action of the coil spring 35. The bushing 32 may be advanced or retracted from the bore 31 to vary the tension of the coil spring and the adjusting screw 26 may be advanced into or retracted from the armature chamber 21 to selectively position the vibrating end 25 of the armature. The actuation of the driving rod in the above manner will cause the engraving point 29 to rapidly vibrate against the work 41 and to etch or engrave the contacted surface thereof. By suitably positioning the bushing 32 and the adjusting screw 26, the stroke of the driving rod may be adapted to any hardness of material being operated upon. I have found that best results are obtained by holding the driving rod perpendicular to the surface of the work and sliding the engraving point along the surface thereof. It is not necessary to force the point into or against the surface of the work, the weight of the device plus the vibratory motion of the point being sufficient to hold the point in engagement with the surface and to produce the desired effect.

As already pointed out, the stroke of the driving rod may be easily and expeditiously adjusted to the particular hardness of the material being operated upon, and the point 39 may be easily sharpened by holding the point at the proper angle against a piece of carborundum, or the like. When desired, a used or broken point may be easily removed from the head of the driving rod and a new one substituted therefor.

Figure 4 illustrates a modification of the head 37. The bushing 32 is provided with a substantially square bore and the head 37 of the driving rod is shaped to conform therewith in a manner to prevent rotation of the head relative to the bushing. The end 42 of the head is tapered and provided with right-angularly disposed cuts which define gripping fingers adapted to engage the engraving point when the chuck 43 is threaded onto the head.

Figure 6 illustrates an attachment which may be applied to the device to produce a burning of the work 41. The attachment comprises a step-down transformer 44 including the conventional core 45, primary coil 46 and secondary coil 47. The leads 48 and 49 of the primary coil lead to a suitable source of current supply, and the leads 50 and 51 of the secondary coil are connected to a clip 52 and a clamp 53, respectively. The clip 52 comprises a split sleeve 54 adapted to be snugly fitted to the enlarged head portion 37 of the driving rod and a depending spring arm 55 carried by the sleeve and frictionally engaging the engraving point. The metallic clamp 53 may be of any suitable shape or construction and includes cooperating jaws 56 and 57 adapted to

grip a portion of the work 41. The transformer 44 will provide a low voltage current which will flow from the transformer through the secondary lead 50 to the engraving point, and, upon engagement of the point with the work, the current will flow through the work to the clamp 53 and through the lead 51 back to the transformer. When the point is applied to the surface of the work 41 the vibratory movement thereof will produce an arcing between the point and the work to burn the surface contacted by the point.

It is to be understood that the form of my invention, herewith shown and described, is to be taken as a preferred example of the same, and that various changes in the size, shape and arrangement of parts may be resorted to without departing from the spirit of my invention, or scope of the appended claims.

Having thus described my invention, I claim:

1. An engraving tool, comprising a casing having an elongated tubular stem, a rod extending axially through said stem and into said casing and being adapted to carry a tool element at the distal end thereof, a vibratory hammer within said casing and adapted to move said rod toward said distal end upon energization of said hammer, means for energizing said hammer, and spring means cooperating with said rod to normally hold the same in pressed engagement with said hammer.

2. An engraving tool, comprising the combination of a casing having an elongated tubular stem, an independently movable rod extending axially through said stem and into said casing and being adapted to carry a tool element at the distal end thereof, a vibratory hammer within said casing and adapted to move said rod element toward said distal end upon energization of said hammer, means for energizing said hammer, spring means cooperating with said rod to normally hold said rod in pressed engagement with said hammer, and adjustable means for varying the tension of said spring means.

3. An engraving tool, comprising the combination of a casing having an elongated tubular stem, an independently movable rod element extending axially through said stem and into said casing and being adapted to carry a tool element at the distal end thereof, a vibratory hammer within said casing and adapted to move said rod element toward said distal end upon energization of said hammer, means for energizing said hammer, an adjustable element carried by said casing and contacting said hammer to regulate the vibratory movement thereof, spring means cooperating with said rod to normally hold the same in pressed engagement with said hammer, and adjustable means to vary the tension of said spring means.

4. An engraving tool comprising the combination of a casing having an elongated tubular stem, a vibratory hammer within said casing, an independently movable rod element having a lateral projection thereon slidably received by the stem, one end of the rod contacting but not connecting with the said hammer and the other end of the rod extending beyond the distal end of the stem, a bushing snugly receiving the extending end of the rod and screw-threadedly received within the bore of the stem for axial adjustment therein, a spring interposed between said projection and the bushing for holding the first-mentioned end of the rod in pressed engagement with the hammer, said spring being selectively tensioned by movement of the bushing relative to

said stem, and a needle element mounted in the extending end of the rod.

5. An engraving tool comprising the combination of electro-magnetic means, a pivoted armature therefor and a rod adapted to carry a needle element at one end and to be actuated axially at its other end by said armature, said rod abutting said armature at a point removed from the pivot of said armature, the end of said armature removed from said pivot being free to move away from said electro-magnetic means, stop means to limit said movement of said armature away from said electromagnetic means, casing means for said electro-magnetic means, axial guide means for said rod associated with said casing means, spring means cooperating with said rod to normally press said rod against said armature and move said armature away from said electromagnetic means and against said stop when not electrically activated, said arrangement being such that when said electro-magnetic means is electrically activated said armature is attracted thereto against the spring pressure on said rod.

6. An engraving tool comprising the combination of a housing containing electro-magnetic means having an armature associated with the upper portion thereof, said housing having its upper wall spaced substantially from said armature when said armature is in the activated position, said housing having an elongated tubular stem, a rod extending axially through said stem and into said housing, said rod being adapted to carry a needle element at one end thereof, spring

means cooperating with said rod to normally press said rod into said housing and against one end of said armature, said armature having its opposite end pivotally held adjacent said electro-magnetic means, said first end being free to move and normally held away from said electro-magnetic means by said rod, said arrangement being such that when said electro-magnetic means is electrically activated said armature is attracted thereto against the spring pressure on said rod.

7. An engraving tool comprising the combination of a housing containing electro-magnetic means having an armature associated therewith, with the upper portion thereof, said housing having its upper wall spaced substantially from said armature when said armature is in the activated position, said housing having an opening therein, a rod adapted to carry a needle element at one end and extending at its other end through said opening and into said housing, spring means cooperating with said rod to normally press said rod into said housing and against one end of said armature, said armature being pivotally mounted with said rod abutting a portion thereof removed from the pivoted part, said armature being free to move away from said electro-magnetic means when the latter is not activated, said armature being normally held away from said electro-magnetic means by said rod, said arrangement being such that when said electro-magnetic means is electrically activated said armature is attracted thereto against the spring pressure on said rod.
